UNITED STATES PATENT OFFICE

ROBERT STRIGEL, OF BERLIN-CHARLOTTEBURG, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

ELECTRIC CIRCUIT WORKING WITH HIGH-VOLTAGE

Application filed May 13, 1929, Serial No. 362,721, and in Germany May 16, 1928.

My invention relates to improvements in an electric circuit working with high-voltage, more particularly a direct current circuit, in which are connected a plurality of electric discharge vessels, more particularly electron, hot-cathode or vacuum tubes.

The object of my invention is to obtain a uniform distribution of the voltage over the individual discharge vessels or electron tubes.

I attain this end in view by providing at the individual electron tubes devices adapted to increase the capacity between the anode and the cathode of the tube, so that by suitably dimensioning the resulting capacities at the individual tubes a uniform distribution of the voltage over all of them is obtained.

I will now describe my invention more particularly with reference to the drawings affixed hereto and forming part of my specification.

In the drawings

Fig. 1 represents a connection diagram of a circuit working with high-voltage, in which a plurality of electron or hot-cathode tubes are connected in series,

Fig. 2, the distribution of the capacity values in the connection system of Fig. 1,

Fig. 3 represents a graph, showing the distribution of the voltage over the individual electron tubes of the system according to Fig. 1,

Fig. 4 represents an electron tube of the character used in Fig. 1 to which my invention is applied,

Fig. 5 represents my improved anode, the hot cathode and the leads to the hot cathode applied to an electron tube according to Fig. 1, and

Fig. 6 represents a modification of the arrangement according to Fig. 5.

When electric discharge vessels (such as high-voltage electron tubes with hot cathodes) worked at high-voltages are connected in series, the voltage is unequally distributed over the individual tubes. With three electron tubes connected in series it has been found that approximately 60 p. c. of the entire voltage falls to the share of the first tube. This may be accounted for by the fact, that the tubes possess not only capacity between

the anode and the hot filament, but also capacity to ground, which latter capacity is of about the same order, and may under certain circumstances become even greater than the capacity between anode and hot filament.

For the series connection of three tubes V_1 , V_2 and V_3 according to the diagram of Fig. 1 the electrostatic conditions exist as shown in the diagram Fig. 2. The point E is connected to ground, S has the full stopping voltage to ground, C_1 , C_2 and C_3 are capacity values of the anode against the cathode of the tubes V_1 , V_2 and V_3 . c are the capacity values of the individual tubes to earth, c_1 being the capacity of the anode of tube V_1 to ground, c_2 being the capacity of the cathode of the tube V_1 and the anode of V_2 to ground, and c_3 the capacity of the cathode of tube V_2 and the anode of tube V_3 to ground. The substitution diagram of Fig. 2 is that of a chain of condensers with simple interlinking. When calculating the voltage distribution for this three-link chain, the distribution as shown in the graph Fig. 3 is obtained.

For the voltage distribution the ratio c/C is a characteristic value and the distribution of the voltage is the more uniform the greater C is in relation to c . In order to render the voltage drop at the high-voltage electron tubes as uniform as possible the capacity of the individual tubes to ground might thus be kept as small as possible. This is possible by suitably spacing the tubes, but here limits exist from the very beginning. As example may be mentioned different spacing of the tubes to ground, mounting on insulators of minimum ground capacity.

The voltage drop might, however, also be made more uniform by increasing C . According to my invention one or a plurality of the tubes connected in series is or are therefore provided with means for additionally increasing the capacity between anode and cathode. This increase of the capacity between the individual anodes and cathodes may at the same time be carried out in such a way, that a stepping of the individual capacity values C results. In this way may be attained a perfectly uniform dis-

tribution of the voltage between the individual tubes. Frequently it is, however, unnecessary to obtain a perfectly uniform distribution of the voltage, and it is sufficient that the tube subject to the highest stresses is suitably relieved. It is then only necessary to increase the capacity of this single tube.

The increase of the capacity between anode and cathode of the individual tubes may be attained in various ways. As illustrated in Fig. 4 of the drawings the caps 1 and 2 at the bushings of the anode and the cathode may, for instance, be provided with disc-shaped lateral extensions or flanges 3 and 4, whereby a considerable increase of the capacity is attained.

Fig. 5 of the drawings illustrates the interior of an electron or hot-cathode tube with the cylindrical anode 5 and the coaxial cathode 6 consisting of a plurality of hot filaments. On end of each anode cylinder here terminates in a disc-shaped extension or flange 7. Opposite this flange 7 is located a second flange 8 mounted on the supporting frame of the hot cathode and in electrical connection with it.

In the design illustrated in Fig. 6 of the drawings the anode cylinder 5 enclosing the hot cathode 6 is extended at one end, so that it also envelopes the leads and bushings of the cathode.

Various modifications and changes may be made without departing from the spirit and scope of the invention.

I claim as my invention:

1. In an arrangement for obtaining an equal voltage distribution in electric high tension circuits, a plurality of electric discharge tubes connected in series in the circuit, each tube having a surface enlargement at one end of its anode and of its cathode, whereby the self capacity between the anodes and cathodes of said tubes is artificially enlarged.

2. In an arrangement for obtaining an equal voltage distribution in electric high tension circuits, a plurality of electric discharge tubes connected in series in the circuit, each tube having a surface enlargement at one end of its anode and of its cathode, whereby the self capacity between the anodes and cathodes of said tubes is artificially enlarged, at least one tube having for this purpose a disc shaped enlargement at the terminal portion of its anode and its cathode.

3. In an arrangement for obtaining an equal voltage distribution in electric high tension circuits, a plurality of electric discharge tubes connected in series in the circuit, each tube having a surface enlargement at one end of its anode and of its cathode, whereby the self capacity between the anodes and cathodes of said tubes is artificially enlarged, at least one tube having a cylindri-

cal anode surrounding the cathode and having for capacity enlargement purposes disc-shaped enlargements on said anode and on said cathode, facing one another.

4. In an arrangement for obtaining an equal voltage distribution in electric high tension circuits, a plurality of electric discharge tubes connected in series in the circuit, each tube having a surface enlargement at one end of its anode and of its cathode, whereby the self capacity between the anodes and cathodes of said tubes is artificially enlarged, at least one tube having a cylindrical anode and a cathode disposed within the anode and having for capacity enlargement purposes enlarged cylindrical cathode terminal surfaces, and a cylindrical anode extension surrounding said terminal surfaces.

In testimony whereof I affix my signature.

ROBERT STRIGEL.
